UNITED STATES PATENT OFFICE.

NORMAN P. HARSHBERGER, OF CHICAGO, ILLINOIS.

SHINGLE.

Application filed October 9, 1924. Serial No. 742,544.

This invention relates to shingles and particularly to flexible shingles which are cut from strips of suitable material. One object of the invention is to provide shingles which can be laid on the roof in such a manner as to present a pleasing appearance. Another object is to form the shingles and to lay them on the roof so as to lock down the exposed edges of the shingles and prevent the edges turning upwardly because of warping or bending by winds or otherwise. Another object is to provide shingles so formed that they can be laid on the roof of a single thickness lapping only sufficiently to prevent leakage and at the same time forming a dependable and waterproof roof covering.

In the formation of the shingles which embody the features of my invention I have provided a shingle which has substantially no surplus material and which can be cut from standard strips without any waste portions being cut from the strips and a further object is to provide a suitable method for cutting out shingles from strips of shingle material. A further object is to provide shingles so formed that they can be assembled on the roof conveniently and expeditiously, certain portions of the shingles forming guides for laying the shingles. Other objects of the invention will be apparent from the accompanying drawings and the following description thereof:

Of the drawings Fig. 1 is a plan view of a strip of shingle material indicating how the individual shingles are cut from the strip; Fig. 2 is a plan view of the assembled shingles on a roof; Fig. 3 is a plan view of an enlarged unit shingle showing the details thereof; and Fig. 4 is a plan view of a modified form of shingle.

The individual shingles 10 are in general shaped like a parallelogram and preferably a square, but at one corner of the shingles I form lugs 11 and 12. When laid on the roof these lugs are on the lower corner of the shingle and are adapted to lie under the respective adjacent under-lying shingles 13 and 14. In this manner the under-lying shingles hold down the exposed corners of the upper shingle. In order to produce this result I provide in the lower edges 15 and 16 of each shingle slits or slots 17 and 18 and in laying the shingles the shoulders 19 and 20 of the lugs 11 and 12 are passed into the slits, as indicated, thus providing a complete locking means for the exposed portions

of the shingles and improving the appearance of the design, and otherwise adding to the value of the invention. The slit assists in preventing the lugs from being forced 60 out from under the other shingle. This slit also provides very effective guide means for laying the shingles, as it is necessary only to slip the shoulders 19 and 20 into the respective slits and force the upper shingle 65 upwardly as far as it will go and it is then in its correct position. As indicated in Fig. 2, the length of these slits is equal to the perpendicular distance from the outer edge of the lug 11 or 12 to the point of connection 70 of the lug to the side of the shingle.

But as a further guide means, and one which is sufficient itself if it is desired, is the recess 21 formed in one of the corners of the shingle which is adapted to receive 75 the corner 22 or the adjacent shingle. In laying the shingles, the shingle 23 has its corner 22 slipped into the recess 21 of the shingle 24. Preferably the edges of the recess 21 are homologous in shape with the 80 edges of the corner 22, and when these two sets of edges coincide the shingle is in its proper place. But by the use of the guides formed by the shoulders 19 and 20 and slits 17 and 18, together with the registering of 85 the recesses 21 and corners 22, the shingles may be very exactly laid.

My method of cutting out shingles of this general shape is indicated by Fig. 1 in which a strip of shingle material is cut into two 90 rows of shingles, and the method consists in cutting pairs of main slits, slits 25 and 26 forming one pair and slits 27 and 28 forming another pair, and in cutting these slits along converging lines to points adjacent to 95 the point 29 where the lines would cross if continued; then in cutting slits 30 and 31 connecting the respective pairs of main slits, and finally in cutting slit 32 which connects the connecting slits 30 and 31. In this manner the lugs 11 and 12 are formed and they are of such shape as to form of proper shape the recess 21. In this instance the pairs of main slits are at right angles to each other, but obviously other angles might be used. 100

Figure 4 shows a modified form of shingle which has a projecting lug 35 and a corresponding recess 36, the lug of one shingle being formed by the material taken from the adjacent shingle to form the recess 36. The 110 edge 37 of the lug is adapted to coincide with the edge 38 of the over-lying adja-

cent shingle. By this arrangement with the edges 37 and 38 registering a double thickness of the exposed edge is formed which adds to the appearance of the shingles when 5 laid on the roof.

I claim as my invention:

1. A shingle having its opposite edges parallel and its adjacent edges perpendicular to each other, and lugs extending outwardly 10 from two adjacent sides at one corner of the shingle; another corner of the shingle having a recess formed therein.

2. A shingle having its opposite edges parallel and lugs extending outwardly from 15 one corner of the shingle, another corner of the shingle having a recess formed therein.

3. A shingle having its opposite edges parallel and lugs extending outwardly from one corner of the shingle, another corner 20 of the shingle having a recess formed therein; and slits projecting inwardly from the edges which are adjacent the said lugs.

4. A shingle having its edges forming substantially a parallelogram but with lugs projecting from one corner, said lugs forming substantially a rectangular parallelogram in combination with a trapezoid; and slits projecting inwardly from the edges of the shingle which are adjacent said corner. 25

5. A shingle having the general shape of a square but with lugs projecting from one corner; said shingle having a recess formed in another corner, the edges of the recess being substantially homologous with the edges 30 of the corner opposite the corner in which the recess is formed.

6. A plurality of shingles laid in rows on a roof, the general contour of each shingle forming a square, and each shingle having 40 a recess in one of its corners into which the corner of an adjacent shingle projects, and a lug extending from the lower portion of each shingle and projecting under the adjacent under-lying shingle.

7. A shingle having two adjacent edges at right angles to each other and a lug extending from the converging ends of the edges, the outer edge of the lug being straight and at an oblique angle with each 45 of the said adjacent edges; and said shingle having a slit projecting inwardly from each of said adjacent edges; and a second lug projecting from one of said adjacent edges, one edge of said second lug being parallel with the said outer edge of the first mentioned lug, said slit commencing at the inner end of said edge of said second lug. 50

with the said outer edge of the first mentioned lug. 5

8. A shingle having two straight converging adjacent edges and a lug extending from the converging ends of the edges, the outer edge of the lug being straight and at an oblique angle with each of said edges, and a second lug projecting from one of said adjacent edges, one edge of said second lug being parallel with said outer edge of said first mentioned lug. 6

9. A shingle having two adjacent edges at right angles to each other and a lug extending from the converging ends of the edges, the outer edge of the lug being straight and at an oblique angle with each of the said adjacent edges; and said shingle having a slit projecting inwardly from each of said adjacent edges; and a second lug projecting from one of said adjacent edges, one edge of said second lug being parallel with the said outer edge of the first mentioned lug, said oblique angles being equal. 7

10. A shingle having two adjacent edges at right angles to each other and a lug extending from the converging ends of the edges, the outer edge of the lug being straight and at an oblique angle with each of the said adjacent edges; and said shingle having a slit projecting inwardly from each of said adjacent edges; and a second lug projecting from one of said adjacent edges; one edge of said second lug being parallel with the said outer edge of the first mentioned lug, the length of the slit being equal to the perpendicular distance from the outer edge of the first mentioned lug to the connection of the lug with one of said sides. 80 85

11. A shingle having two adjacent edges at right angles to each other and a lug extending from the converging ends of the edges, the outer edge of the lug being straight and at an oblique angle with each of the said adjacent edges; and said shingle having a slit projecting inwardly from each of said adjacent edges; and a second lug projecting from one of said adjacent edges, one edge of said second lug being parallel with the said outer edge of the first mentioned lug, said slit commencing at the inner end of said edge of said second lug. 90 95 100 105

In testimony whereof, I hereunto set my hand.

NORMAN P. HARSHBERGER.

DISCLAIMER

1,663,658.—*Norman P. Harshberger*, Chicago, Ill. SHINGLE. Patent dated March 27, 1928. Disclaimer filed March 26, 1935, by the assignee, *Bakelite Building Products Co. Inc.*

Hereby enters this disclaimer to claims 1, 2, 5, and 6 inclusive, in said specification, which are in the following words, to wit:

“1. A shingle having its opposite edges parallel and its adjacent edges perpendicular to each other, and lugs extending outwardly from two adjacent sides at one corner of the shingle; another corner of the shingle having a recess formed therein.

“2. A shingle having its opposite edges parallel and lugs extending outwardly from one corner of the shingle, another corner of the shingle having a recess formed therein.”

“5. A shingle having the general shape of a square but with lugs projecting from one corner; said shingle having a recess formed in another corner, the edges of the recess being substantially homologous with the edges of the corner opposite the corner in which the recess is formed.

“6. A plurality of shingles laid in rows on a roof, the general contour of each shingle forming a square, and each shingle having a recess in one of its corners into which the corner of an adjacent shingle projects, and a lug extending from the lower portion of each shingle and projecting under the adjacent under-lying shingle.”
